* cited by examiner

Primary Examiner — Garth Rademaker*Assistant Examiner* — Samantha Q Lawrence(74) Attorney, Agent, or Firm — Wenderoth, Lind & Ponack, L.L.P.(57) CLAIM

The ornamental design for a house, as shown and described.

DESCRIPTION

FIG. 1 is a front view of a first embodiment of a house.

FIG. 2 is a back view thereof.

FIG. 3 is a top plan view thereof.

FIG. 4 is a right side view thereof.

FIG. 5 is a left side view thereof.

FIG. 6 is a front view of a second embodiment of a house.

FIG. 7 is a back view of the second embodiment of FIG. 6.

FIG. 8 is a top plan view of the second embodiment of FIG. 6.

FIG. 9 is a right side view of the second embodiment of FIG. 6; and,

FIG. 10 is a left side view of the second embodiment of FIG. 6.

The broken lines depict portions of the house that form no part of the claimed design.
